(57) **CLAIM**

The ornamental design for a curved end floating cooler, as shown and described.

DESCRIPTION

FIG. 1 is a top perspective view of a curved end floating cooler showing my new design.

FIG. 2 is a bottom perspective view thereof.

FIG. 3 is a top plan view thereof.

FIG. 4 is a right side view thereof.

FIG. 5 is a left side view thereof.

FIG. 6 is a bottom plan view thereof.

FIG. 7 is a rear view thereof;

FIG. 8 is a front view thereof;

FIG. 9 is a perspective view thereof with the lid removed; and,

FIG. 10 is a right side view thereof with the lid removed. The broken lines showing the interior of the cooler, that is visible when the lid is removed, form no part of the claimed design.
